UNITED STATES PATENT OFFICE.

JOHN L. TAYLOR, OF OAKMONT, PENNSYLVANIA.

METAL BARGE CONSTRUCTION.

1,253,645.

Specification of Letters Patent. Patented Jan. 15, 1918.

Application filed May 21, 1914. Serial No. 839,973.

To all whom it may concern:

Be it known that I, JOHN L. TAYLOR, a citizen of the United States, residing at Oakmont, in the county of Allegheny and 5 State of Pennsylvania, have invented a new and useful Metal Barge Construction, of which the following is a specification.

My invention relates to the construction of barges, boats, pontoons or other open or 10 decked floating craft, used in passenger traffic or for conveying cattle or in handling and conveying merchandise, coal, sand and like materials or products, both packaged and in bulk.

15 Heretofore such vessels have been generally formed of wood. In the few cases where metal has been used the flat plates employed in forming the sides and bottom necessitate the use of a large number of stiffeners. The use of such a large number of 20 stiffeners not only adds to the weight and decreases the carrying capacity of the craft but, on account of the short distance between the stiffeners, seriously interferes 25 with the unloading operations in removing bulk cargoes, in which cases a grab bucket is employed.

In a barge framed in the usual manner with wooden dunnage, it is necessary to 30 remove the dunnage several times during the life of the barge, at periods varying from four to seven years, and, at intervals not exceeding two years, it becomes necessary to remove the dunnage in order to clean and 35 paint the barge bottom.

In a metal barge having a wooden dunnage and engaged in carrying cargoes such as coal or sand, all or part of which is finely divided enough to drop between the cracks, 40 which are formed by the alternate wetting and drying of the dunnage, the space between the bottom plating and the dunnage soon becomes filled, and results in a serious loss in cargo carrying capacity.

45 One object of my invention is to provide a barge or similar floating craft framed of metal and having novel means whereby the necessary stiffness and strength is obtained with a material reduction in dead weight 50 and consequent increased carrying capacity

on a given draft or with a reduction in draft in carrying a given weight.

Another object of the invention is to provide a metal barge construction having improved means by which the number of 55 frames used in the barges is lessened to a large extent and the use of the grab buckets ordinarily employed in removing bulk cargoes thereby greatly facilitated.

A further object of this invention is to 60 provide a barge in which the necessary number of punched holes in the plating and number of rivets used in fabricating the craft are reduced to a large extent, leakage and liability of leakage is lessened, the cost 65 of upkeep is reduced and the life of the craft is lengthened.

A still further object of my invention is to provide a barge having novel means for strengthening the barge framing, lessening 70 the liability of sinking of the barges and facilitating the raising of sunken loaded barges.

Another object of my invention is to provide a barge construction whereby the number 75 of necessary bottom stiffening members is greatly reduced, liability of engagement of the stiffening members by grab buckets employed in unloading operations is avoided and consequent injury or damage to the 80 barge thereby overcome and prevented.

A further object of my invention is the provision of an open barge having a bottom constructed in such manner that the cargo can be loaded directly upon the bottom plating, the necessity of the wooden dunnage usually employed in a steel barge of ordinary construction is avoided and the dead weight is thereby decreased with a corresponding increase in the cargo carrying 90 capacity.

A still further object of the invention is to provide a barge, the cargo of which can be entirely removed down to the bottom plating by the ordinary unloading methods. 95

A still further object of this invention is to provide a barge, having all parts easily accessible for cleaning, inspecting, painting or repairing.

Still further objects of my invention will 100

become apparent as the invention is more fully disclosed hereinafter.

Referring to the accompanying drawings forming part of this specification, Figure 1 5 is a plan showing the left hand half of a barge framed of metal and constructed and arranged in accordance with my invention, the barge being symmetrical about the line I—I. Fig. 2 is a sectional side elevation of 10 the part of the barge shown in Fig. 1, the section being taken on the line II—II of Fig. 1. Fig. 3 is a transverse section taken on the irregular line III—III of Fig. 1. Fig. 4 is a sectional elevation, on an enlarged 15 scale, showing in detail the transverses used in the construction of Figs. 1, 2 and 3, the section being taken on the line IV—IV of Fig. 3.

Fig. 5 is a plan showing half of the length 20 of a modified construction, the barge being symmetrical about the line V—V. Fig. 6 is a side elevation or outboard profile of the barge shown in Fig. 5. Fig. 7 is a transverse section on the irregular line VII—VII 25 of Fig. 5. Fig. 8 is a sectional side elevation showing the construction of the rake ends of the barge of Figs. 5, 6 and 7.

Fig. 9 is a transverse section of a barge 30 having corrugated plates forming the sides as well as the bottom thereof. Fig. 10 is a sectional side elevation of a portion of the barge construction of Fig. 9 the section being taken on the line X—X of Fig. 9, and showing the construction of the transverses 35 and of the diagonal bracing employed to take the shear on the corrugated metal side plating of the barge.

Fig. 11 is a transverse section of a barge 40 having a deck, the left hand half of this figure showing the diagonal bracing forming part of the deck supporting means and the right hand half showing the construction of the decked barge having transverse water tight bulkheads. Fig. 12 is a sectional elevation of a portion of a barge this section being taken on the line XII—XII of Fig. 11.

Fig. 13 is a plan showing a portion of a 50 modified form of barge. Fig. 14 is a sectional side elevation of the barge construction shown in Fig. 13. Fig. 15 is a detail sectional end elevation showing a portion of the barge shown in Figs. 13 and 14. Fig. 16 is a detail sectional end elevation, on the 55 line XVI—XVI of Fig. 15 showing the construction of the transverses of the barge of Figs. 13, 14 and 15.

Fig. 17 is a sectional end elevation showing a further modification in the construction 60 and arrangement of the corrugated side and bottom plating and in the construction of the transverses and side stiffeners of the barge. Fig. 18 is a sectional end elevation

taken on the line XVIII—XVIII of Fig. 17. Fig. 19 is a section taken on the line 65 XIX—XIX of Fig. 17.

In the accompanying drawings, referring to Figs. 1, 2, 3 and 4 a barge having vertical sides 2 and rake ends 3 formed of flat plates and a bottom 4 formed of corrugated plates 70 is shown. Plating is provided at each end of the barge, which extends horizontally inward to form a deck 5 and which is joined to an inclined plating wall 6 so as to form a water tight bulkhead or compartment 7 75 in each end of the barge. The plates forming the rake ends of the barge are connected at their upper edges to a steel corner casting 8, this casting being riveted at its ends to the plating forming the sides 2—2 of the 80 barge.

The barge bottom 4 is formed of a series of corrugated plates, the corrugations being formed of flat portions 9—10 joined by inclined portions 11 so as to be trough shaped 85 in cross section, and the corrugations extending lengthwise parallel with the length of the barge so as to form a strong, rigid bottom.

Transverses 12 are positioned at suitable 90 intervals in the length of the barge which extend lengthwise along the bottom from one side to the other of the barge. As shown these transverses are formed of two inclined sides 13—13 which with the bottom 4 of the 95 barge form water tight compartments 14 of triangular cross section, the bottom of the barge forming one side of the so formed triangle.

In constructing the transverses 12 (see 100 Fig. 4) so as to form a water tight compartment, a rolled steel angle 15 extends lengthwise from one side to the other of the barge at the apex of the transverses and forms a convenient means for connecting the adjoining upper edges of the plates 13—13 forming the inclined sides of the transverses. Angles 16—16 also are employed at intervals in the length of the plates 13 to form stiffeners for the inclined sides of the transverses, the upper ends of these angles being connected together by gusset plates 17. Angles 18 are riveted to the lower edge of the side plates 13 and to the bottom plates 4, one flange of these angles being bent to the 115 same shape as the corrugated bottom plates to form an air and water tight joint. Joined by its lower edge to the upper edge or apex of each transverse 12 at each side of the barge is a plate 19 forming a knee which is 120 fastened to the side of the barge by means of an angle 20. Stiffening angles 21 are secured to the inner inclined edge of the plate 19 in forming the knees.

Between the transverses 12 and also between the end transverses and the ends of 125

the barge is a series of side stiffeners 22—22 which as shown are conveniently formed of rolled metal angles. An angle 23 extends lengthwise along each side of the barge forming the knuckles to which the bottom edge of the side plating 2 and the outer edge of the corrugated bottom plating 4 are secured by rivets or equivalent fastening means.

Extending lengthwise at the upper edge of each side of the barge is a metal channel 24 having its flanges turned downward as shown, the channels being riveted by one flange to the sides 2 of the barge. The upper ends of the knees formed by the plates 19 and angles 20—21 are fastened to the channels 24 and also the upper ends of the stiffeners 22 and the lower ends of the stiffeners 22 are secured to the bottom plating by means of angles or bent plates 25. Secured on top of each of the channels 24 and also on the upper edge of the castings 8 on the ends of the barge is wooden planking 26 forming the gunwales of the barge.

In the sides of each of the hollow transverses 12 is a manhole having a water tight man-hole cover 27 and the horizontal plating forming the decks 5 at each end of the barge is provided with a man-hole and man-hole cover 28.

The barge is provided with the usual complement of towing bitts 29 and 30 on opposite sides of each end thereof to provide means by which the barges are lashed or hitched together with the lines or ropes employed in making up a tow of barges and the towing lines also are fastened to these bitts, when the barge is being towed from place to place.

In the construction shown in Figs. 5, 6, 7 and 8 of the drawings the sides 2, and rake ends 3 are formed of flat plates and the bottom plating 4 is corrugated, the bottom plating having flat portions 9 and 10 connected by inclined portions 11 formed in the same manner as in Figs. 1, 2, 3 and 4. Secured on each end of the transverses 31, which are formed of rolled I-beams, are knees 32 formed of a web plate and angles 33, 34 and 35. Each end of the barge is provided with a horizontal deck 5 and sloping plating wall 6 which serve to form a water and air tight compartment 7 in each end of the barge, and in this case diagonal bracing formed of angles 36 is also provided to stiffen the rake ends 3 and deck plating 5 and plating 6. On each side of the barge, between the transverses 31 and also between the end transverses 31 and ends of the barge, are vertically extending channels 37 secured by one flange to the side plating 2 to stiffen the sides of the barge. The channels 24 and wooden planking 26 extending along the up-

per edge of the barge sides forms the gunwales of the barge and the upper ends of 65 the knees 32 are fastened to the channels 24 as in Figs. 1, 2, 3 and 4. Towing bitts 29 and 30 are secured to the gunwales of the barge and a man-hole having a cover 28 is formed in each of the decks 5. The lower 70 edge of the sides 2 are connected by knuckles 23 formed of angles to the edges of the corrugated bottom plating 4 of the barge, the angles 23, as shown, being placed outside of the side and bottom plating. 75

In the construction of Figs. 9 and 10 the barge has corrugated plating forming the sides 2 as well as the bottom plating 4 of the barge. The rake ends may be formed either of corrugated or flat plates as is desired. 80 Transverses 38 formed of I-beams and knees 32 formed in the same manner as in Fig. 7 are fastened to the bottom and the side plating in the manner which has been described and channels 24 with downwardly 85 turned flanges are fastened to the side plating 2 and to the top of the knees 32. In this construction no vertically extending angle stiffeners are employed, the corrugated side plating having sufficient stiffness in itself 90 and diagonally extending angles 40 (see Fig. 10) fastened to the corrugated side plating 2 between the transverses 38 are provided to take the shearing strain on the sides 2 of the barge. 95

In Figs. 11 and 12 a decked barge is shown. In this construction the barge has flat side plating 2 and corrugated bottom plating 4, a round knuckle 41 being employed to connect the lower edge of the side 100 plating with the adjacent edge of the corrugated bottom plating.

Transverses formed of channels 42 are employed at intervals in the length of the barge, these transverses being secured by one 105 flange to the corrugated bottom plating 4. A plate 43 and stiffener angles 44 and 45 are used at the sides 2 of the barge to connect the ends of the transverses 42 and side plating 2. 110

At the upper ends of the vertical stiffeners formed by the plates 43 and angles 44, 45 a channel 46 is secured which extends from side to side of the barge, this channel being bent to the same curvature as the deck 115 of the barge which is formed of flat metal plates 47. A series of channels 48 which rest on the upper flange of the curved channels 46 form deck beams for supporting the deck plating 47 and an angle 49 at each 120 upper edge of the barge sides is used to connect the side plating 2 and deck plating. 125

Struts 50 are used to connect the transverses 42 and top transverse channels 46 and diagonal bracing formed of angle-bars 51— 52 also is employed to connect the top chan-

nel and the transverses (as is shown on the left hand half of Fig. 11). At each end of the barge and at suitable intervals in the length of this barge, a bulkhead is formed 5 of flat plates, which (as shown on the right hand half of Fig. 11), extends from the deck plating 47 downwardly to the bottom plating and from side to side of the barge so as to form water tight compartments at intervals 10 in the length of the barge. The bottom angles 53 are bent to the contour of the corrugated bottom plating so as to form a tight joint. Vertical stiffeners formed of angles 54 are used to stiffen the bulkhead. 15 Between the transverses and between the water tight bulkheads a series of angles 55 are used to form vertical stiffeners for the side plating, the lower ends of these stiffener angles being fastened to the bottom plating 20 and the upper ends to the deck plating 47.

Referring now to the construction shown in Figs. 13, 14 and 15 and, in detail, in Fig. 16, the sides 2 of the barge are formed of flat metal plates, and the bottom plating 4 is 25 constructed of plates having sinuous corrugations 57 with the corrugations extending lengthwise in a direction parallel to the length of the barge. Angles 58 (see Fig. 15) forming the square knuckles used in this 30 construction are employed to connect the adjacent marginal side edges of the plating forming the sides 2 and bottom 4, these angles extending up the rake ends 3 to the upper marginal edges or gunwales of the 35 barge. As shown, the corrugations 57 in the bottom plating decrease in depth toward the top edge of the rake ends of the barge although obviously the same result is obtainable by continuing the corrugations at a uniform 40 depth around and up the rake ends 3 of the barge. An angle 59 is secured by one leg to the upper edge of the rake end plating, the other leg thereof being riveted to the plating forming the decks 5 at the ends 45 of the barge, as is shown in Figs. 13 and 14.

Located within the barge at suitable intervals in the length thereof are the transverses 60 which, in the construction of Figs. 13, 14, 15 and 16 are H-shaped in cross section, being built up (as shown in detail in Fig. 16) of angles 61 riveted on opposite sides of each of the marginal edges of a central connecting web member 62. Wooden fillers 63 are placed in the spaces between 55 the angles 61 on each side of the web 62 so as to prevent the grab-buckets used in unloading the barges from catching or grasping the transverses and in this way possible damage to the barge is avoided and overcome. 60

The vertical stiffeners or uprights on the transverses 60 are formed of channels 64 placed back to back with a gusset plate there-

between forming a knee 65 by which the vertical members are secured to the ends of the horizontally extending bottom members of the transverses 60. Angles 66 are fastened by one leg to the channels 64 at the ends thereof, the other leg of these angles being riveted directly to the plating forming the sides 2 of the barge. 70

The upper ends of the channels 64 are fastened to the channels 24 forming the gunwale on each side of the barge, one flange of these channels being riveted to the side plating 2. The channels forming the gunwales are extended beneath the plating forming the decks 5 so as to afford means for securing the marginal side edges of the deck plating to the upper edges of the side plating 2 80 of the barge. Angles 68 on the inclined edge of the knee 65 serve to stiffen the plate forming this knee. 85

The intermediate vertical side stiffeners are formed of short pieces of angles or bent plates 69, one leg of these angles being fastened to the plating 2 forming the barge sides, the other leg being riveted to the angles 70 extending continuously from the top to the bottom of the barge sides 2. 90

The Z-bars which extend horizontally at intervals in the height of the barge to form the side stiffeners 71 are secured by one leg to the plating forming the sides 2, and the Z-bars are fastened by one leg to the vertical members 64 of the transverses 60 and to the angles 70 forming part of the intermediate side stiffeners 69 at the points of intersection therewith so as to strengthen the flat sides of the barge between the transverses 60 and 100 vertical intermediate side stiffeners 69.

Man-holes in the decks 5 at the ends of the barge provide means of access to the compartments 7 and, when the covers 28 are secured in position in the man-holes, an air 105 and water tight compartment 7 is formed in each end of the barge when the partition or wall 85 is extended to the bottom of the barge as before described.

The use of the transverses at such widely 110 separated intervals in the length of the barge is accomplished and made possible by reason of the very stiff and strong construction obtained in the use of corrugated metal plating in constructing the barge bottoms as 115 shown in Fig. 15 or the sides and bottoms of the barges as in Figs. 17, 18 and 19.

In Figs. 17, 18 and 19 a modified form of construction is shown in which the plating forming the sides 2 of the barge is corrugated, with sinuous corrugations 72 as well as the plating forming the bottom 4. The side and bottom plating may be formed in one continuous length as shown, and the sinuous corrugations may be made of such 125 size as will permit of bending to form the

rounded knuckle or a separate plate forming the knuckle 80 may be used to which the abutting ends of the side and end plating are riveted (in the manner shown in Fig. 17). 5 The corrugated bottom plating is continued around the rake ends 3, preferably in the same manner as shown in Fig. 14.

The transverses 74 in Figs. 17 and 18 are of modified construction, being formed of 10 plates bent into the shape of inverted U with angles 75 riveted by one leg to the marginal edges of the said shaped plates. The outstanding legs of the angles 75 are utilized in riveting the corrugated bottom plating 4 of the barge to the transverses 74. At each 15 end of the transverses, a vertical member 76 is provided, also formed of a plate bent into U shape and having one leg of an angle 77 riveted to each marginal side edge of the U-shaped plate, the other leg of these angles being in direct contact with and riveted to the corrugated side plating 2.

In this construction the horizontal side stiffeners used in the construction of Figs. 25 13, 14 and 15 are dispensed with and the intermediate vertically extending side stiffeners of the preceding figures are also omitted. Plates 78 secured to the vertical members 76 and the ends of the horizontal members 30 forming the transverses 74 afford means for bracing and fastening these vertical members to the transverses of Fig. 17, and bent plates 79 are employed to connect the ends of the transverses to the rounded knuckles 80 of the barge. The plates 78 forming the knee are stiffened along their inclined marginal edge by angles 82. The upper ends of the vertical members 76 in this construction are connected to and support the channel 35 beams 24 secured by one flange to the top marginal edge of the side plates in forming the gunwales, in the same manner as heretofore described.

With some constructions made in accordance with this invention, such as for example that shown in Fig. 17 in which the plates forming the sides of the barge are corrugated, the number of intermediate side stiffeners may be materially reduced or in 40 some cases may be entirely omitted.

The advantages of my invention will be apparent to those skilled in the art. Corrugating the metal plating stiffens and strengthens the barge to an extent which 5 permits the number of transverses used to be largely reduced. The omission of the large number of transverses and side stiffeners made possible by corrugating the barge plating greatly decreases the number of 0 rivet holes in the construction and to that degree lessens the amount of leakage or possible leakage in the completed structure. The reduction in number of rivet holes and

rivets and in the amount of riveting necessary also materially reduces the first cost 65 of the fabricated structure.

By forming the bottom of the barge of corrugated metal plates, the wooden dunnage, usually employed, is made unnecessary, and the presence of projections on the 70 bottom of the barge liable to be engaged by the grab buckets in loading and unloading, is avoided.

Having corrugated plating forming the 75 sides and bottom, such barges are lighter in weight than barges of equal strength, as framed heretofore and barges constructed in accordance with my invention have a greater cargo carrying capacity, require less time in erecting, and the cost of making the 80 barges is materially reduced. The construction of a metal barge having a corrugated bottom supplies the need for a light weight metal barge which is particularly adapted to the river carrying trade and which can 85 be provided at a cost approximating that of wooden barges.

Modifications in the construction and arrangement of the parts can be made without departing from my invention. The barges 90 may have corrugated sides and bottom with a square knuckle instead of the rounded knuckle shown in Fig. 6. The transverses of Fig. 17 may be employed in forming the barges of the other figures. The intermediate 95 side stiffeners and the horizontally extending stiffeners may be employed or not, as is desired. The water tight compartments in the ends of the barge, and the hollow transverses forming water tight compartments at intervals in the length of the barge may be employed or not as is desired. The corrugations may be sinuous as shown in Figs. 15, 16, 17, 18 and 19 or may be 100 formed in the manner shown in the other 105 figures. The corrugations may be terminated short of the rake ends of the barges and other changes may be made within the scope of my invention as defined in the appended claims. 110

I claim:—

1. A barge or similar floating craft comprising sides, rake ends and a bottom formed of metal plates, a deck at each end of the barge, plating connected to the deck and bottom to form water tight compartments in the ends of the barge, and a series of cross frames or transverses between the ends of the barge, said transverses being hollow and being triangular in cross section with the barge bottom forming one side thereof, and forming water tight compartments. 115

2. A barge or similar floating craft comprising sides, rake ends and a bottom formed of metal plates, a deck at each end 120 of the barge, plating connected to the deck 125

- and bottom to form water tight compartments in the ends of the barge, and a series of cross frames or transverses between the ends of the barge, at least one of said transverses being hollow and being triangular in cross section with the barge bottom forming one side thereof and forming a water tight compartment intermediate the ends of the barge.
- 10 3. A barge or similar floating craft comprising sides, rake ends and a bottom formed of metal plates, a deck at each end of the barge, plating connected to the deck and

bottom to form water tight compartments in the ends of the barge, and a series of 15 cross frames or transverses between the ends of the barge, at least one of said transverses being hollow and being triangular in cross section and forming a water tight compartment intermediate the ends of the barge. 20

In testimony whereof, I have hereunto set my hand.

JOHN L. TAYLOR.
